United States Patent Office.

JAMES COULTER AND HERBERT HARPIN, OF HUDDERSFIELD, ENGLAND.

Letters Patent No. 98,850, dated January 18, 1870

IMPROVEMENT IN STONE-DRESSING MACHINES.

The Schedule referred to in these Letters Patent and making part of the same.

To all whom it may concern:

Be it known that we, JAMES COULTER and HERBERT HARPIN, of Huddersfield, in the county of York, and Kingdom of England, have invented new and useful Improvements in Means or Apparatus for Facing or Dressing Flags, or Smoothing the Surface of Stones; and we do hereby declare that the following is a full and exact description thereof, reference being had to the accompanying drawings, and to the letters of reference marked thereon; that is to say—

This invention consists in combining, with a rotary work-supporting face-plate, a reciprocating skeleton carriage or frame, located above it, and adapted for carrying loosely other stones to be dressed; in the combination, with a flanged reciprocating frame, of guide-pulleys, for supporting and guiding the same; and in the mechanism whereby the reciprocating frame may be vertically adjusted.

Flags or stones to be dressed or scoured, are fixed upon the face-plate by means of portable dogs, stops, or blocks, temporarily fixed in holes provided in the face-plate for that purpose, with wooden wedges driven in betwixt; and other flags or stones to be faced, are placed within the reciprocating frame, resting upon the stones fixed on the face-plate. When motion is given to the apparatus, the flags in one part will rub those in the other part, sand and water being supplied thereto, as usual in scouring flags by hand. The reciprocating frame may be provided with upright guides, for holding flags or stones on edge, in proper position for squaring them.

This invention is illustrated by the accompanying drawings, in which—

Figure 1 is a vertical longitudinal section of an apparatus constructed according to our invention, and

Figure 2 is a plan of the same.

A is the face-plate or table, mounted on a spindle, B, and supported in bearings C and C', fixed on suitable frame-work.

On this spindle B is fixed a bevel-wheel, D, gearing into another bevel-wheel, mounted on the driving-shaft E. The latter-mentioned bevel-wheel is driven by a fixed key or feather therein; and, by means of the driving-pulleys F and F' on the said shaft, motion is given to the table. This said bevel-wheel is capable of being moved into and out of gear by means of a friction-box worked by hand-wheel G, screw and rod G', and lever G'.

H is the reciprocating frame, which is supported upon four friction or carrying-rollers, I, and is maintained in lateral position by other four friction-rollers J, which act against four guide-plates K, fixed on the frame H. It is also prevented from vertical displacement by the flanges of the frame, which project slightly beneath the rollers J, which thus hold it

down. These rollers are carried on studs fixed in brackets L, which brackets are capable of being raised and lowered, or moved up and down on the hollow pillars M, (to regulate the height of the frame according to the thickness of the stone under operation,) by means of screws N, which are turned or operated by hand-wheel, key, or other suitable means.

Motion is given to the reciprocating frame H by means of a rod, O, connected thereto, and to a lever, P, to which is also attached another rod, Q, connecting the same to a stud on a bevel-wheel, R, which is driven by another bevel-wheel, S, fixed on the spindle B.

Provision is made, by means of holes in lever P, for regulating the length of stroke or travel of the table. The relative speeds of the table and frame are so arranged as to be continually changing the points of contact of the stones operated upon.

T are flags or stones, placed on the table (in a rough state) to be faced, and which are fixed thereon by means of wedges U, driven in betwixt dogs or stops U', which fit into holes provided in the table for that purpose.

V are other flags or stones, (also in their rough state,) placed loosely within the reciprocating frame H, and resting upon the stones T.

It will be readily seen, that when rotary motion is given to the table, and reciprocating motion to the frame, the surfaces of the stones in the frame, which are in contact with the surfaces of the stones fixed on the table, will rub or grind each other. Water and sand (which are to be supplied to the tops) will pass betwixt the stones in the frame to the surfaces in contact, and assist in the grinding thereof, as usual in facing or scouring flags or stones by hand.

By means of this invention, flags and stones may be taken, in their natural rough state, and rubbed or ground to a perfectly true or even smooth surface, without the previous use of any sort of chisel or other cutting-tool or instrument.

Figure 3, sheet 2, is an elevation, and

Figure 4 is a plan of a table with reciprocating frame, having upright guides and frame-work thereon, for holding flags or stones on the edge to be edged, and also to be squared.

Figure 5 shows a top view, on a larger scale, of a portion of the frame-work with a stone therein.

A¹ are the upright guides or stands, which are fixed to cross-bars D' on the reciprocating frame, and in which guides are formed vertical grooves a. The frame-work B¹ is formed with ribs b, to fit and slide in the aforesaid grooves.

Flags to be edged or squared, are fixed, by means of wood wedges c, in these frames, and the frames are then placed in the grooves of the guides or stands, (in which they are free to slide up or down,) with the

bottom edges of the said flags resting upon the flags or stones which are fixed on the rotary table.

When the machine is set in motion, the flags are edged or rubbed, and made straight on the bottom edges; they are then turned in the frames, with the straightened edge fitted and wedged up to one of the upright sides of the frame, by which means they are set square or at right angles to the surface of the table, with other rough edges toward and in contact with the stones fixed on the table, which, on the machine being again set in motion, will be rubbed or ground and straightened, in like manner as the former edges, and will also be squared or rubbed to straight edges at right angles to the former straightened edges; consequently squared.

Figure 6 is a vertical cross-section, and

Figure 7 is a plan of a table, with a frame thereon, constructed for retaining wall-stones whilst being rubbed or faced, and by means of which they can also be squared and thickened. The ribs or bars of this frame being vertical, or at right angles to the table, the rubbed edges or sides are placed and wedged against these ribs; consequently the edges or sides toward the table will be ribbed square with the former edges or sides, and so on to any or all the remaining edges or sides.

Figure 8 is a longitudinal and vertical section of a portable apparatus for scouring flags, being the same in principle as that shown in figs. 1 and 2, but of a modified construction and mode of operation.

The table A² is formed with a rim or flange on the under side, so as to be supported on friction-rollers B²,

and teeth or cogs are also provided underneath, forming a bevel-wheel, in which a bevel-pinion, C², gears, and which is mounted on the driving-shaft D², giving rotary motion to the table.

A worm, E², is also keyed on the driving-shaft, which gears in a worm, F², having a stud, f, to which a connecting-rod, G², is attached, and by which motion is given to the reciprocating frame.

Shafts H² and I², each connect and are supported by two brackets, H¹ and I¹, and have pinions J¹ and J² at each end, gearing into racks K¹ and K², formed or fixed on the pillars L¹ and L².

A worm, M², gears in a wheel keyed on each shaft H² and I². By the turning of the handle N², the said brackets can be raised and lowered as required.

We claim—

In a machine for dressing stone, the combination of a rotary work-supporting face-plate, with a reciprocating skeleton carriage or frame located above it, and adapted for carrying loosely other stones to be dressed.

Also, the combination of the flanged reciprocating frame, with the guide-pulleys, in the manner shown and described.

Also, the combination, with the hollow pillars M, of the separately adjustable screws N and sliding brackets L, as and for the purpose described.

JAMES COULTER.
HERBERT HARPIN.
